UNITED STATES PATENT OFFICE.

EDWIN E. SLICK, OF PITTSBURG, PENNSYLVANIA.

ROLLING-MILL FEED-TABLE.

SPECIFICATION forming part of Letters Patent No. 746,886, dated December 15, 1903.

Application filed June 2, 1902. Serial No. 109,852. (No model.)

To all whom it may concern:

Be it known that I, EDWIN E. SLICK, of Pittsburgh, Allegheny county, Pennsylvania, have invented a new and useful Rolling-Mill Feed-Table, of which the following is a full, clear, and exact description, reference being had to the accompanying drawings, forming part of this specification, in which—

Figure 1 is a partial side elevation showing a three-high mill provided with my improved feed-table, and Fig. 2 is a top plan view of the same.

My invention relates to the feed-tables used in rolling-mills having passes at different levels, whether in the same or different sets of rolls; and it is designed to provide a simple switching mechanism which will be lifted as the metal issues from the lower pass and will then guide the piece upwardly to an upper pass on its return movement.

In the drawings, in which I show my invention as applied to a three-high mill for rolling angles, 2, 3, and 4 represent the three rolls having suitable passes therein for shaping the metal. The first pass (indicated at a) is between the middle and upper rolls, the second pass b is between the middle and lower rolls, the third pass c is between the middle and upper rolls, and the fourth pass d is between the middle and lower rolls.

In front of the pass b and at the level of the pass between the middle and lower rolls is a receiving-trough 5, in the end portion of which is placed a pair of feeding-rollers 6. These rollers are shown as provided with a groove shaped to fit the angle or other piece being rolled, and the lower roll is positively driven, while the upper rests by gravity upon the metal and is frictionally driven. The pass in the rollers 6 is in line with the pass b, and the metal issuing from this pass feeds along the trough 5 and into the bite of the rollers 6. As the metal thus issues from the rolls it passes beneath the lower end of and lifts a swinging trough 7, secured to a cross-bar 8, pivoted in bearings 9, and the last end of the issuing metal is drawn out by driving the rolls 6 until its rear end passes the lower end of the trough 7. This trough, which is preferably formed of a channel shape, is cut away or beveled off at its bot-

tom, and on reversing the movement of the rollers 6 the metal being fed back to the rolls will slide up within the trough 7, and thus be guided by a deflector 10 to the upper pass c. In the form shown the metal then returns to the lower pass d and into the trough 11, along which it is fed by rollers 12.

The advantages of my invention result from the use of the inclined tilting trough, which is lifted to allow the emerging metal to pass under it and then drops down to direct the metal upwardly as it is returned to the mill.

The swinging trough may be arranged at an angle to the lower trough to deflect the metal sidewise and may lead the metal to another set of rolls, and many other changes may be made in the form and arrangement of the parts without departing from my invention.

I claim—

1. The combination with a rolling-mill, having passes at different levels, of a table or trough extending outwardly from a pass at a lower level, a downwardly-inclined trough or table extending down from an upper pass into the path of the metal on the lower table, and having at least a portion thereof arranged to swing, and mechanism for feeding the metal outwardly on the lower table to a point beyond the lower end of the inclined trough, substantially as described.

2. A feed-table having a lower receiving-trough, and a swinging downwardly-inclined trough arranged to be lifted as the metal enters the lower trough, the lower end of the inclined trough terminating at an intermediate point in the length of the lower trough; substantially as described.

3. A feed-table for a mill having passes at different levels having a lower receiving-trough and a swinging downwardly-inclined trough normally resting therein, said inclined trough being arranged to be lifted by the metal fed into the lower trough and to deflect the metal upwardly as it is fed back to the rolls; substantially as described.

4. A rolling-mill feed-table having a lower trough, a swinging downwardly-inclined trough normally resting therein and arranged to be lifted by the metal, and mech-

anism for feeding the metal back to the rolls through the inclined trough; substantially as described.

5. A rolling-mill feed-table having a plurality of rollers arranged to receive the issuing metal between them, reversing driving connections for the rollers arranged to drive them in either direction to feed the metal out or feed it back to the rolls, and mechanism 10 for guiding the metal to another pass on its backward feed; substantially as described.

6. The combination with a rolling-mill having a plurality of passes arranged to successively receive the metal, of a stationary roll-

ing-mill feed-table whose feeding mechanism 15 consists solely of a plurality of rollers arranged to receive the metal being rolled between them, and driving connections arranged to rotate the rollers in either direction to feed out the metal or to feed it back 20 to another pass of the rolls; substantially as described.

In testimony whereof I have hereunto set my hand.

EDWIN E. SLICK.
